UNITED STATES PATENT OFFICE.

JAMES A. SCOTT, OF NEW HAVEN, CONNECTICUT, ASSIGNOR TO FRED H. BENTON, OF SAME PLACE.

PAPER BOX.

SPECIFICATION forming part of Letters Patent No. 332,951, dated December 22, 1885.

Application filed September 14, 1885. Serial No. 176,987. (No model.)

To all whom it may concern:

Be it known that I, JAMES A. SCOTT, of New Haven, in the county of New Haven and State of Connecticut, have invented a new Improvement in Paper Boxes; and I do hereby declare the following, when taken in connection with accompanying drawings and the letters of reference marked thereon, to be a full, clear, and exact description of the same, and which said drawings constitute part of this specification, and represent, in—

Figure 1, a perspective view of the box complete, showing a portion of the cover broken away, and showing in broken lines an extension from the upper side as a modification; Fig. 2, the blank from which the box is cut, on a reduced scale; Figs. 3, 4, and 5, perspective views illustrating the manner of folding and interlocking the parts.

This invention relates to an improvement in that class of paper boxes which are open, to be closed by a removable cover of some character—that is to say, a box having a bottom, two sides and ends, the top open, to be closed by the cover—and particularly to that class in which the body of the box is cut complete from a single piece, and so that the parts, bent into proper angles to each other, may be interlocked and secure the box in the set-up condition, and so that the blanks may be shipped in a flat condition and readily set up by the consumer, the object of the invention being the construction of a box in which there shall be little waste of material, and in which the locking shall be strong, and so that there will be no tendency from pressure upon the inside to disengage the locking parts; and it consists in the construction, as hereinafter described, and more particularly recited in the claim.

In Fig. 2 I show the blank as cut from a single sheet of paper or other suitable material to form the complete box. Solid lines indicate the cuts in the blank and broken lines the scores where the folds are to be made.

The central portion, A, represents the bottom of the box. On one edge of the bottom is the one side B, and on the opposite edge the side C. At one end of the bottom is an extension, D, corresponding to the shape of 50 the end of the box, and a further extension,

E, to form a flap. At the opposite end of the bottom is a like extension, F, for that end, and from that projects a like flap, G. At one end of the side B is a longitudinal extension, H, in which a segmental slit is cut to form a tongue, a. From the other end is a like extension, I, in which is a longitudinal slit, b. At one end of the side C is a flap, J, like the flap H on the side B, and in like manner constructed with a segmental-shaped slit to form a tongue, a, and upon the opposite end is a like extension, K, having in it a longitudinal slit, b. The length of the extensions H I J K should be substantially equal to the width of the bottom. The side B is turned upward at 55 right angles to the bottom A, as indicated in Fig. 3, and the extension H turned inward at right angles to the side B, as seen in that figure. Then the opposite side, C, is in like manner turned upward, as seen in Fig. 4, and the extension K in like manner turned inward at right angles to its side and inside the extension H, and the slit b passes down over the tongue a, so that the tongue a comes upon the inside of that end of the box, and as clearly 60 seen in Fig. 4. Then the end portion, D, is turned upward, as seen in Fig. 5, outside the two extensions H K, and the flap E is then turned over the upper edge of the two parts H K and down into the box, as seen in Fig. 65 4, and tucked between the part K and the tongue a, as clearly seen in Fig. 1. The opposite ends are in like manner folded and locked. The end is thus formed in three thicknesses, the two inner thicknesses interlocked 70 the one with the other, and the outer thickness covering the upper edge of the two, to give a finished appearance to that edge, and tucked into the tongue a, securely locks the parts in the set-up condition, and the box is 75 substantially as firm as a pasted box. The cover may be made in substantially the same manner, or formed by any of the usual constructions; or it may be made as a part of the box itself, one side—say B—being extended for 80 that purpose, as indicated in broken lines, Fig. 2.

This construction of box is very desirable for shoes, corsets, and other articles of manufacture which require the larger class of boxes, 85 90 95 100

and may be made in telescopic form, each part being substantially alike, save that one is made so much smaller than the other that the one may inclose the other in the usual manner, the application of the covers, or what may be called the "cover," being so common and well known as not to require illustration or particular description.

I have described the tongues as formed by 10 a segment-shaped slit; but it will be understood that other shaped cut—say as indicated in broken lines, Fig. 2—will serve the purpose, it only being essential that the tongue may be substantially vertical when the box is set up.

15 I claim—

The herein-described blank for paper boxes, consisting of the central portion, A, side portion, B, upon one edge, and the other side portion, C, upon the opposite edge, the bot-

tom portion constructed with an extension, D, 20 at one end, and F at the opposite end, corresponding to the ends of the box, the said extensions D F further extended to form a flap, sides constructed with an extension at each end corresponding substantially to the end of 25 the box, one of said extensions having a slit therein to form a tongue, a, the extension at the opposite end of the same side having a longitudinal slit, b, therein corresponding to said tongue, the said blank slit between the 30 extension from the sides and bottom, and the blank scored for the bends, substantially as described.

JAMES A. SCOTT.
